UNITED STATES PATENT OFFICE

2,077,151

SEWING MACHINE

Carl O. Nelson, Chicago, Ill., assignor to Union
Special Machine Company, Chicago, Ill., a cor-
poration of Illinois

Application November 19, 1934, Serial No. 753,671

9 Claims. (Cl. 112—181)

This invention relates to sewing machines and more particularly to machines of the lockstitch type.

The object of the invention is to provide in a sewing machine of this type, stitch forming mechanism, including an improved rotary hook and bobbin carrier with the elements of the mechanism so formed and interrelated as to permit the machine to be operated at a greater speed than has heretofore been possible.

It has been customary with such machines to employ a stationary bobbin holder and a surrounding rotary hook which, incident to its rotation, carries the needle thread loop around the bobbin holder and ultimately releases the loop to form the stitch. To provide for the release of the needle thread loop, the annular bearing elements between the rotating and stationary parts of the mechanism are cut away throughout a limited portion of their circumference. When these cut out areas coincide, release of the thread loop is permitted, the take-up mechanism for the needle thread being designed to draw the thread through the opening thus provided. With a machine which is operated at ordinary speeds, the release of the needle thread loop over the bobbin holder does not occasion any serious difficulty, but as the speed of the machine is increased beyond the range of hitherto customary speeds, the release of the needle thread loop cannot be accomplished by the means usually provided for that purpose.

With the higher speeds there is presented on the one hand the problem of providing adequate bearing surfaces between the stationary and rotating parts of the hook, for such surfaces must extend substantially throughout the circumference of the hook, and this imposes a definite limitation upon expanding the size of the opening through which the needle thread loop is released. On the other hand, the higher speeds reduce the time interval of the thread release, making it necessary for the take-up mechanism to draw the needle thread through the opening with a very high linear velocity. The momentum imparted to the needle thrust incident to the upward pull thereon will cause the thread to break if its movement is obstructed, or if it impinges upon sharp edges in its passage through the opening in the bearing surfaces, and this in turn imposes a definite limitation upon restricting the size of the opening through which the release is effected.

The present invention is characterized by interfitting bearing surfaces between the elements 50 of the rotary hook which are so formed as to

provide adequate circumferential engagement and at the same time permit escape of the needle thread loop without obstruction in the path of its movement; and it is further characterized by a relation between the stitch forming and take-up mechanism which effects the release of the needle thread loop sufficiently before it attains its maximum take-up velocity, to prevent the loop from being drawn taut against the surfaces over which it passes. Moreover, one of the bearing surfaces 5 adjacent to the cut away portion thereof is beveled in the direction of the thrust upon the needle thread incident to its take-up, thus permitting the needle thread loop to be eased through the opening through which it is released without impinging 10 upon sharp edges.

Other more specific advantages characteristic of the present invention will become more apparent from the description hereinafter set forth of one embodiment or example of the practice thereof, having reference to the accompanying drawings. Of the drawings:

Fig. I represents a side elevation of a sewing machine embodying my invention, with certain parts cut away for clearness of illustration.

Fig. II represents an end elevation of the same, with the cover plate removed to reveal the needle actuating and take-up mechanism.

Fig. III represents a view showing parts of the take-up mechanism, the needle, the rotary hook, 30 and bobbin holder, illustrating the relative positions of these parts when the take-up lever is at its maximum elevation.

Fig. IV represents a view similar to Fig. III, but showing the relative positions of the parts 35 later in the cycle of operation and when the needle is in its lowermost position.

Fig. V represents a view similar to Fig. III, but showing the relative positions of the parts as the needle emerges from the bobbin case in its upward 40 travel.

Fig. VI represents a view similar to Fig. III, but showing the relative positions of the parts as the needle continues in its upward movement and while the take-up arm is at its lower limit of 45 travel.

Fig. VII represents a view similar to Fig. III, but showing the relative positions of the parts after the take-up lever has commenced its upward movement.

Fig. VIII represents a view similar to Fig. III, but showing the relative positions of the parts just prior to the release of the needle thread loop from the raceway of the rotary hook.

Fig. IX represents a view similar to Fig. III,

but showing the relative positions of the parts at the point where the needle thread loop is released from the raceway of the rotary hook.

Fig. X represents an enlarged detailed view of the rotary hook and bobbin holder showing the same in the positions occupied at the point of release of the needle thread loop from the raceway.

Fig. XI represents a plan view of the rotary hook and bobbin holder in the same relative positions as represented in Fig. X.

Figs. XII, XIII and XIV represent enlarged fragmentary views of the rotary hook and bobbin holder with parts thereof cut away, showing respectively the successive positions of the rotary hook before the needle thread loop is released from the raceway, at the point of release, and immediately after such release; and,

Figs. XV, XVI and XVII represent cross-sectional views, taken as indicated by the lines XV—XV, XVI—XVI and XVII—XVII in Figs. XII, XIII and VI, respectively.

The sewing machine selected for illustration in the drawings is of the type described in the pending application for U. S. Letters Patent, Serial No. 670,186, filed May 9, 1933, of Norman V. Christensen and Charles F. Rubel. As most clearly shown in Fig. I it comprises generally a supporting bed 31, which serves as the cloth plate of the machine, and a standard 33 having an overhanging arm 34. At the end of the overhanging arm, there is mounted a reciprocating needle bar 35 carrying a needle 36. The needle bar 35 is connected to a main shaft 37, extending within the overhanging arm 34, by means of a crank 38, a crank arm 39, and a link 40, the latter being attached at its lower end to a collar 42 on the needle bar 35. Rotation of the main shaft 37 is accomplished through a belt pulley 43, and the main shaft 37 is connected through gears 44, 45, 46 with an operating shaft 47 at the base of the machine, which is driven at the same speed as the main shaft 37. The movements of the feed mechanism, comprehensively designated at 48, are derived from the operating shaft 47, but such movements are not material to the present invention and are therefore not described herein. An auxiliary shaft 49, carrying a rotary hook 50 is connected to the operating shaft 47 by gears 51, 52 which are so proportioned that the rotary hook 50 is given two rotations to one rotation of the main shaft 37.

As most clearly shown in Fig. II, the take-up mechanism for the needle thread is mounted within the end of the overhanging arm 34, and such mechanism derives its movement from the crank 38 on the main shaft 37. A take-up lever 54 is pivotally attached to the crank 38 by a pin 55, and intermediate its ends the take-up lever 54 is pivotally attached to a swinging link 56 fulcrumed at 57. Associated with the take-up mechanism are the usual thread guiding and tensioning devices as indicated at 58, 59, 60, 61. At the end of the overhanging arm 34 there is also provided a presser foot 62 for holding the material on the work support. By means of a spring 63, the presser foot is yieldingly depressed. An elevating lever 64 is employed for raising the presser foot 62. The parts described above are of usual construction, and it will be apparent that this invention may be applied to many different forms of lockstitch machines, and that the particular machine shown in the drawings represents merely one convenient example serving to illustrate the practice of the invention.

In Figs. III—IX, inclusive, there is represented a series of views showing successive positions of the take-up mechanism and the rotary hook 50, which assist in explaining the timing relation between these elements which is characteristic of the present invention. In these figures, the path designated by the thread carrying end of the take-up lever 54 is divided into thirty equal time divisions, designated by the numerals 1 to 30, each division representing the movement of the take-up lever corresponding to 12° of rotation of the main shaft 37. The point designated at 1 has been arbitrarily selected and is the point at which the needle 36 is in its lowermost position. It will be noted that the take-up lever 54 moves downwardly from the point 1 to the point 11 with substantially uniform speed and then proceeds upwardly from the point 11 with accelerating angular velocity. At approximately the point 16 the maximum angular velocity is reached, and from there to the point 22, which represents the upper limit of travel, the velocity diminishes. Downward movement from the point 22 to the point 1 proceeds at a substantially uniform rate. From the take-up lever 54 the needle thread 65 leads downwardly through a needle clamping device 66 to the eye 67 of the needle, and from thence to the work, indicated at 68. From the bobbin holder 69 the bobbin thread 70 leads upwardly through an aperture 71 in the work plate 72, and from thence to the work 68.

In the example illustrated, in which the rotary hook 50 has two revolutions for each double stroke of the needle bar 35, the position of the rotary hook 50, when the take-up lever 54 is at its upper limit, and while the needle 36 is moving downwardly towards the rotary hook 50, is as represented in Fig. III. In Fig. IV the position of the parts is shown at the point where the needle 36 has penetrated the work 68, the work plate 72 and the bobbin holder 69, and has reached its lowermost position. As the needle 36 moves upwardly from this position, and the rotary hook 50 revolves in a clockwise direction, the needle thread 65 is engaged by the beak 73 of the rotary hook, as shown in Fig. V, and a loop thus drawn from the needle is represented at 74 in Fig. VI, and is there shown carried part way around the stationary bobbin holder 69. In this position the take-up lever 54 has reached its lower limit of travel, and the needle 36 has passed upwardly through the work plate 72 and the work 68.

With continued rotation of the rotary hook 50, the loop 74 is drawn up with rapidly accelerating velocity by the take-up lever 54, and it is shifted from the beak 73 of the rotary hook 50 to the nose 75 which is disposed oppositely thereto. The parts then assume the positions represented in Fig. VII. The movement of the take-up lever 54 continues at a gradual speed and tends to contract the loop 74 to a shape substantially as represented in Fig. VIII. Eventually, the loop 74 is released from bearing elements between the rotary hook 50 and the bobbin holder 69, as illustrated in Fig. IX. The loop 74 is retained for an instant upon the nose 75 of the rotary hook 50 and is finally cast clear of the rotary hook to form a stitch. It will be noted that at the point 70 where the loop is released from the bearing elements between the rotary hook 50 and the bobbin holder 69, as shown in Fig. IX, the take-up lever 54 is still moving upwardly with accelerating angular velocity and has not attained its maxi-

- mum speed. Moreover, at this point the linear velocity of the needle thread 65 is also still accelerating, and has not reached its maximum value.
- 5 In order to obtain the conditions of release of the needle thread loop as described above, the bearing elements between the rotary hook 50 and the bobbin holder 69 are formed in a special manner, one example of such special shaping being 10 shown in Figs. X and XI, and they are disposed in a particular relation to the take-up mechanism. As there shown, the bobbin holder 69 is in the form of a cylindrical ring having a peripheral bearing rib 76 which extends substantially around 15 its circumference, but which is cut away or interrupted to form a clearance space 87 through which the needle thread loop may be released. The rib 76 engages with an annular bearing groove 77 on the underside of the rotary hook 50. 20 The leading end of the peripheral rib 76 adjacent to this clearance space 87 is formed with the usual abrupt shoulder 78 constituting a detaining horn upon which the thread loop is caught during the first part of its passage around the bobbin holder 25 69. The trailing end of the peripheral rib 76 is provided with a beveled surface 79 at one side, and is desirably tapered downwardly towards the cut away or clearance space 87 through which the thread loop is released. The beveled surface 79 is 30 also inclined transversely in a direction leading downwardly from the needle side of the bobbin holder 69 to the opposite side, and the adjacent surfaces of the rib are rounded to avoid sharp edges.
- 35 It will be particularly observed that the bearing face 80 at the needle side of the peripheral rib 76 is preserved as a vertical bearing surface extending substantially to the region of the cut out, whereas the bearing face 81 at the opposite side is 40 considerably shortened. It is important that the bearing elements between the bobbin holder 69 and the rotary hook 50 shall have adequate circumferential engagement to prevent excessive vibration and to maintain the proper alignment 45 between these parts. The bobbin holder 69 is held against rotation by means of a notched formation 83 which is loosely engaged by a lug 84. As it is not rigidly fixed in its position, the bobbin holder 69 has capacity for slight movement and is subjected to an axial thrust in a direction towards the lug 84 as the bobbin thread is drawn from the bobbin casing 85. By preserving the vertical bearing face 80, so that it is substantially coextensive in its 50 circumference, with the length of the rib 76, this thrust is adequately resisted and excessive play between the rib 76 and the bearing groove 77 is prevented. Moreover, the bearing groove 77 extends substantially to the beak 73 at one side of a 55 clearance space 88 through which the thread is released and substantially to the nose 75 at the other side of the opening.

60 As appears in Figs. X and XI, at the point where the thread loop 74 is released from the raceway, the take-up thrust upon the needle thread is in a direction diagonally across the rib 76 towards the needle opening 86 in the bobbin holder 69 and in a direction diagonally upward from the bobbin holder 69 towards the needle opening 71 in the 65 work plate 72. The beveled surface 79 at the trailing end of the rib 76 is thus inclined to conform substantially to the direction of the pull on the needle thread with the result that the thread loop 74 is eased around the end of the rib preparatory 70 to its release, preventing its being drawn taut 75

against the surface thereof at the critical moment of its passage.

This condition is more clearly illustrated in Figs. XII, XIII and XIV, from which it will be noted that the thread loop 74 has capacity for appreciable contraction between the point where it is caught around the bearing elements, which is shown in Fig. XII, and the point where it is free to be released from the raceway, which is shown in Fig. XIII. Following the release of the thread 10 loop 74 from the raceway, the loop is retained for an instant upon the nose 75, as illustrated in Fig. XIV, thus preventing the thread from twisting, and it is ultimately cast completely clear of the 15 rotary hook.

The cross sectional views represented in Figs. XV and XVI, also serve to illustrate how the needle thread loop 74 is eased over the trailing end of the rib 76 with the loop riding up on the beveled surface 79 immediately prior to its release. 20

The difficulty which has heretofore been experienced with rotary hooks in attempting to operate lockstitch machines at higher than customary speeds is that the thread is drawn taut and stretched beyond its elastic limit before it 25 is released from the rotary hook, with resultant breaking of the thread. When a sewing machine is operated at a speed of, say, 5000 revolutions of the main shaft per minute, it will be appreciated that the thread is taken through the needle eye at 30 a very high velocity—it may be in excess of 100 miles an hour at the point of maximum speed—and if the release of the thread loop does not occur until after this speed is reached, there will be a pronounced jerk at the bight of the thread 35 which extends around the bearing elements. If at this point any interference is offered to the free movement of the thread or to the contraction of the thread loop, the thread will break. By forming the bearing elements of the rotary 40 hook and bobbin holder in the manner of this invention, and by advancing the time of the release of the thread loop from the raceway, so that such release takes place before the take-up reaches its maximum velocity, it is possible to 45 operate sewing machines at speeds which have not heretofore been obtained.

While I have described one example of the practice of my invention, with reference to a sewing machine having a specific form of take-up 50 mechanism and rotary hook, it will be apparent that many changes may be made in the form of the apparatus herein described without departing from the spirit of the invention as defined in the annexed claims.

55 Having thus described my invention, I claim:

1. In a sewing machine, a rotary hook and a bobbin holder having annular interengaging bearing elements interrupted for a relatively small portion of their circumferences to afford clearance spaces permitting release of the needle thread loop as it pass over the bobbin holder, and reciprocatory mechanism for taking up the needle thread loop with an accelerating velocity, the clearance spaces of said bearing elements being 60 so disposed as to permit release of the needle thread loop before it attains its maximum velocity, and one of the bearing elements having the end adjacent to its clearance space shaped to ease the thread loop preparatory to its release, 65 thereby preventing its being drawn taut against the surface of said bearing element.

2. In a sewing machine, a rotary hook and a bobbin holder having a peripheral bearing element engaging said rotary hook throughout the 75

- major portion of its circumference, said bearing element being cut away to permit release of the needle thread loop as it passes over the bobbin holder, reciprocatory mechanism for taking up 5 the needle thread loop with an accelerating velocity, the trailing end of said bearing element being so disposed as to permit release of the needle thread loop before it attains its maximum 10 velocity and being shaped to ease the thread loop preparatory to its release, thereby preventing its being drawn taut against the trailing end of said bearing element.
3. In a sewing machine, a rotary hook and a bobbin holder having interengaging annular 15 bearing elements, interrupted for a relatively small portion of their circumferences to afford clearance spaces permitting the release of the needle thread loop as it passes over the bobbin holder, one of said bearing elements being formed 20 adjacent its clearance space with a beveled end over which the needle thread loop is released, take-up mechanism for the needle thread loop, and means for reciprocating said mechanism with the velocity of the take-up accelerating during 25 the upward stroke, said beveled end being so disposed as to permit release of the needle thread loop sufficiently before it attains its maximum take-up velocity to prevent the needle thread loop from being drawn taut against the surface of 30 said bearing element.
4. In a sewing machine, a rotary hook and a bobbin holder having a peripheral rib engaging said rotary hook throughout the major portion of its circumference, said rib being cut away to 35 permit the release of the needle thread loop as it passes over the bobbin holder, and having the trailing end thereof formed with a beveled edge over which said needle thread loop is released, take-up mechanism for the needle thread loop, 40 and means for reciprocating said mechanism with the velocity of the take-up accelerating during the upward stroke, said trailing end of the rib being so disposed as to permit release of the needle thread loop sufficiently before it attains 45 its maximum take-up velocity to prevent the needle thread loop from being drawn taut against said rib.
5. In a sewing machine, a rotary hook and a bobbin holder having interengaging annular 50 bearing elements interrupted throughout a relatively small portion of the circumference of the rotary hook to afford clearance spaces permitting the release of the needle thread loop as it passes over the bobbin holder, and take-up mechanism 55 for the needle thread loop, one of said bearing elements being formed adjacent to its clearance space with a tapered end beveled substantially in the direction of the thrust on the needle thread loop incident to its take-up so as to prevent said loop from being drawn taut against an edge thereof.
6. In a sewing machine, a rotary hook, a bobbin holder having a peripheral rib engaging said rotary hook throughout the major portion of its circumference, and take-up mechanism for the needle thread loop, said rib being cut away to 5 permit the release of the needle thread loop as it passes over the bobbin holder, and having the trailing end thereof formed with a beveled surface inclined substantially in the direction of the thrust of the needle thread loop incident to its 10 take-up.
7. In a sewing machine, a rotary hook, a bobbin holder having a peripheral rib engaging said rotary hook throughout the major portion of its circumference, and take-up mechanism for the needle thread loop, said rib being cut away to 15 permit the release of the needle thread loop as it passes over the bobbin holder, and having the trailing end thereof gradually tapered towards the cut away portion and transversely beveled to provide an inclined surface leading downwardly 20 from the needle side of the bobbin holder towards the opposite side thereof.
8. In a sewing machine, a rotary hook formed with an internal bearing groove, a bobbin holder in the form of a cylindrical ring having an opening through which the needle passes and having a peripheral rib engaging said groove throughout the major portion of its circumference, and take-up mechanism for the needle thread loop, said 25 rib being cut away to permit the release of the needle thread loop as it passes over the bobbin holder and having the trailing end thereof formed with a surface inclined transversely downward from the needle side of the rib to the opposite side thereof.
9. In a sewing machine, a rotary hook formed with an internal bearing groove, a bobbin holder having an opening through which the needle passes and having a peripheral rib with bearing faces at the sides thereof engaging said groove 30 throughout the major portion of its circumference, and take-up mechanism for the needle thread loop, said rib of the bobbin holder being cut away in the vicinity of the needle opening to permit the release of the needle thread loop 35 as it passes over the bobbin holder and having the trailing end thereof formed with the bearing face at the needle side extending substantially to the needle opening and with the opposite bearing face beveled to ease the passage of the needle 40 thread loop prior to its release.

CARL O. NELSON.
